UNITED STATES PATENT OFFICE.

FERNLEY H. BANBURY, OF ANSONIA, CONNECTICUT, ASSIGNEE TO BIRMINGHAM IRON FOUNDRY, OF DERBY, CONNECTICUT, A CORPORATION.

MACHINE FOR TREATING RUBBER AND OTHER HEAVY PLASTIC MATERIAL.

Application filed February 23, 1923. Serial No. 538,743.

To all whom it may concern:

Be it known that I, FERNLEY H. BANBURY, a citizen of the United States, residing at Ansonia, in the county of New Haven and State of Connecticut, have invented a new and useful Improvement in Machines for Treating Rubber and Other Heavy Plastic Material; and I do hereby declare the following, when taken in connection with the accompanying drawings and the characters of reference marked thereon, to be a full, clear, and exact description of the same, and which said drawings constitute part of this application, and represent, in—

Fig. 1 a sectional view of a machine for treating rubber and similar material, constructed in accordance with my invention.

Fig. 2 a broken sectional view illustrating a charging-opening at one side of a double cylindrical case.

Fig. 3 a sectional view illustrating my invention as applied to a single cylindrical case, with a central charging-opening.

Fig. 4 a similar view illustrating my invention as applied to a single cylindrical casing, with a charging-opening at one side of the center thereof.

This invention relates to improvement in machines for treating rubber and other heavy plastic material in which a casing is employed with a charging-opening in the top of the casing, a vertically-movable closure for said casing, and one or more rotors in the said casing. Some means must be provided for conveniently raising the closure, and the object of this invention is to provide a simple arrangement of parts whereby the closure may be conveniently raised or lowered, and the invention consists in the construction as will be herein-after described and particularly recited in the claim.

In carrying out my invention, as shown in Fig. 1 of the drawings, I employ a stationary or non-tilting casing 5 having two cylindrical chambers 6 and 7, respectively containing rotors 8 and 9. The top of the casing has a charging-opening 10 for which I provide a vertically-movable closure 11, while the bottom of the casing has a discharge-opening 18 for which I provide a horizontally-movable closure 19. The said charging-opening 10 opens upwardly into the lower end of an upstanding housing or

neck 20, providing a bearing for the closure 55 11 and furnished at one side with an offsetting hopper 21. For the operation of the said closure I employ a long threaded stem 12 extending upward through the said neck and also through a chambered head 14 60 mounted directly upon the upper end thereof and receiving a wheel-like nut 13 held against vertical displacement by it. The said nut 13 carries an annular worm-gear 15 meshed into by a worm-shaft 16 driven, from 65 any convenient source of power, in one direction for lifting the closure 11 above the bottom of the hopper 21 and in the opposite direction for permitting it to descend into position to close the charging-opening 10. 70

Instead of arranging the charging-opening centrally of a double cylindrical casing, it may be arranged over one of the chambers 7, as shown in Fig. 2 of the drawings; or, in case of a single cylindrical chamber 75 17 is employed, as shown in Fig. 3 of the drawings, the charging-opening may be arranged centrally thereof, or at one side thereof, as shown in Fig. 4 of the drawings.

I claim:

In a machine of the class specified, the combination with a stationary casing having a charging-opening in its top and a discharge-opening in its bottom, of a rotor, a horizontally-movable closure for the said 85 discharge opening, a vertically-movable closure for the said charging opening, a neck rising from the casing and providing a housing for the said vertically-movable closure, a hopper discharging into the said 90 neck, a chambered head mounted upon the upper end of the said neck, a threaded stem connected at its lower end with the vertically-movable closure and extending upward through the said neck and head, a nut located within the said head, held against 95 displacement thereby and receiving the threaded upper end of the said stem, an annular worm-gear upon the periphery of the said nut, and a worm-shaft meshing into 100 the said annular worm-gear.

In testimony whereof, I have signed this specification in the presence of two subscribing witnesses.

FERNLEY H. BANBURY.

Witnesses:

FREDERIC C. EARL,
MALCOLM P. NICHOLS.
